UNITED STATES PATENT OFFICE.

JAMES G. HENDRICKSON, OF BAYONNE, NEW JERSEY, ASSIGNOR TO HARRY S. BENSON AND WILLIAM A. READ, OF BAYONNE, NEW JERSEY.

CHANGE-SLIDE.

SPECIFICATION forming part of Letters Patent No. 690,280, dated December 31, 1901.

Application filed April 19, 1901. Serial No. 56,643. (No model.)

To all whom it may concern:

Be it known that I, JAMES G. HENDRICKSON, a citizen of the United States, residing at Bayonne, in the county of Hudson and State of New Jersey, have invented new and useful Improvements in Change-Slides, of which the following is a specification.

This change-slide is adapted for the delivery of coin or the like, so as to enable the same to be readily taken by the recipient; and the invention resides in certain novel features of construction set forth in the following specification and claims and illustrated in the annexed drawings, in which—

15 Figure 1 is a perspective view of the slide or device. Fig. 2 is a plan view of Fig. 1. Fig. 3 is a sectional side elevation of Fig. 2, the gate being closed. Fig. 4 shows the gate opened and also shows a somewhat-modified 20 form of lever. Fig. 5 shows a modified arrangement of gate.

The delivery apparatus is shown comprising a gutter or chute the bottom of which is indicated at *a* and sides at *b*. This chute may 25 lead from or form part of a plate or table or platform part. In the drawings this latter is shown with bottom *a'* and sides *b'* of enlarged separation or which lead toward the chute in a taper or funnel-like manner. The bottom 30 *a* is shown fixed or rigid or of one piece throughout, so that a purchaser or person receiving change placing or pressing his hand or finger-tips from underneath against bottom *a* will find a steady or immovable support.

35 The front or mouth of the chute is open, so that change can slide or drop out at such front or lower free end on the opening of the gate, which latter, as seen, comprises the front part or gate proper, *c*, and sides *d*, hinged or jointed at *e*. The gate or door can drop shut by its weight; but a spring or springs *f*, applied in practice to close or help in closing the gate, have been found serviceable. The gate is shown with its sides at the outside of the 40 chute or sides *b*, and the cuts or breaks at *g* in said chute sides allow the gate-front *c* to close or drop clear to the bottom *a*.

When the gate is closed, coin or objects sliding down the chute are arrested against 45 gate-front *c*; but on opening or raising the latter these objects can slide down out of the

chute into the hand of the recipient. The gate is opened by a lever shown doubled or in form of a bail or with two arms; but the description of one lever-arm explains the operation. This lever or its arms *o* are each provided with or mounted on a fulcrum or pivot *h* on sides *b*. The free or rear end of arm *o* engages the gate or side *d* at a suitable point or stud *i*, and the power-point of the lever is shown in form of a head or thumb-button *k*. The fingers of the hand being placed against the under side of bottom *a* and the thumb pressing on knob *k* above the bottom, the lever is swung to open or lift the gate for 60 the coin to slide into the hand. The knob being then released or the hand removed, the gate drops or is closed by spring *f*. This spring can be suitably applied by being coiled about hinge *e* and braced at points or studs 65 *l* and *m* at sides *d b'*.

The device can be applied to use as required. It can be mounted on a foot or post or secured to or have its part *a'* sunk in or flush with a table or counter, as at the delivery or paying window of a bank or railroad or ticket office, or it might be applied or suspended at the side or top of such window above the counter, so that if by accident the change should miss or jump past or out of 80 the hand of the customer such change or coin will land on the counter instead of falling on the floor. These details, however, are for the user to arrange as required and need not be dwelt on herein.

85 The bottom *a* can be corrugated or ridged to prevent coin adhering. Ridges are shown at *n*. In Fig. 1 the lever-arm *o* is shown simply resting against stud or point *i*, while in Fig. 4 the resistance portion of the lever 90 is shown slotted or made to straddle or fork about this stud, and such latter arrangement it has been found will prevent the lever or its handle *k* from jumping or swinging unnecessarily from bottom *a*.

95 In Fig. 5 is shown an arrangement for having the gate close from below up instead of from above down. The pivot or hinge *e* is here shown below bottom *a*, and this bottom is slotted or cut, so that a passage is formed 100 by which the gate *c* can swing down and up between the sides *b*, the latter in this in-

stance being unbroken or uncut, so that the complete or unbroken sides *b* form a support for bottom *a*. The gate part or arm *d'* is linked at *p* to lever *o*, and as the button *k* is 5 pressed toward bottom *a* the gate *c* opens or swings down. The spring *f* normally holds the gate or the lever in closing position.

What I claim as new, and desire to secure by Letters Patent, is—

- 10 1. A coin or change delivery or slide comprising a chute having a fixed bottom and sides, an open front or delivery, a gate, and a lever for actuating the gate, said sides having a cut-away portion to allow the gate to 15 close to the bottom substantially as described.
- 20 2. A coin or change slide comprising a chute having a fixed bottom, a gate, and a lever for actuating the gate, said lever having a knob or thumb-button located above the bottom so that the fingers and thumb of a hand can clasp the bottom and button for pressing the latter toward the bottom substantially as described.
- 25 3. In a device of the character described,

an inclined chute, a gate pivoted to the sides 25 of said chute and adapted to close the same intermediate its ends, a pair of studs carried by said gate, a pair of springs suitably connected to said gate, and a lever pivotally connected to the sides of said chute and engaging said studs for operating the gate.

4. In a device of the character described, a chute having an open front or delivery-mouth, a gate suitably pivoted to the sides of said chute and adapted to close the mouth or 35 open front thereof, means for normally retaining said gate in a closed position, and a lever pivoted to the chute and engaging with the gate for elevating the gate to open the mouth or open front of the chute.

In testimony whereof I have hereunto set my hand in the presence of two subscribing witnesses.

JAMES G. HENDRICKSON.
